CONTROL DEVICE FOR BREATHER TYPE
STORAGE TANKS

John H. Wiggins, Chicago, Ill.

Application March 3, 1937, Serial No. 128,717

8 Claims. (Cl. 220—85)

This invention relates to storage tanks of the breather type that are used to hold gases and volatile liquids, and particularly to the control devices used in such structures for venting the tank to prevent an abnormal or dangerous pressure from being created therein, and/or to admit air to the tank to prevent a dangerous minus pressure from developing in the tank.

One object of my invention is to provide a control device of the general character above mentioned that is inexpensive to construct, easy to install and in which the coacting parts are of novel construction and arrangement.

Another object of my invention is to provide a volume control valve or a combined volume control and vacuum vent valve for breather type storage tanks which is of such design that it can be easily combined with a conventional flame arrester without modifying or changing the construction of the flame arrester.

And still another object of my invention is to provide a control device of the general type mentioned, that comprises a single flame arrester arranged between the tank and a gas chamber to which air is admitted by a vacuum vent valve, and from which gases are permitted to escape by opening a volume control valve that is actuated or unseated by the movement of the roof of the tank.

Figure 1 of the drawing is a fragmentary vertical, transverse sectional view of a breather type storage tank equipped with a control device constructed in accordance with my present invention, and Figure 2 is an enlarged view of said control device partly in elevation and partly in vertical section. In the drawing, A designates a storage tank that may be used for holding gases or volatile liquids, and B designates a breather type roof for said tank, which is of such construction and arrangement that it is capable of flexing upwardly from the position shown in Figure 1 so as to increase the volume of the gas space of the tank. When the roof B is in the position shown in Figure 1, it is sustained by beams I that may be supported in any preferred manner.

The tank A is equipped with a novel control device herein illustrated as consisting of a combined volume control and vacuum vent valve C mounted on the roof B and having provision for permitting gases to escape automatically from the tank A when the roof flexes upwardly to a certain approximate position and having provision for permitting air to enter the tank A so as to prevent an abnormal minus pressure from

being created therein during the operation of withdrawing or discharging the material or substance confined in the tank. The valve C may be mounted directly on a collar 2 that surrounds a hole in the roof B, but I prefer to combine said valve with a flame arrester D through which escaping gases travel before entering the valve C. Any suitable type or kind of flame arrester may be employed, the one herein illustrated being of conventional construction and being attached to a cover plate 3 on the collar 2 carried by the roof B of the tank. The valve C is mounted on the upper end of said flame arrester and hence the flame arrester constitutes a passageway for gases that are caused to escape from the tank to vent the same, and it also constitutes a passageway for air that is admitted to the tank to prevent a dangerous minus pressure from being created.

Preferably the valve C comprises a body or casing 4 whose interior constitutes a gas chamber X that is always in direct communication with the gas space of the tank through the passageway formed by the flame arrester D, and said gas chamber X is provided at its upper end with a gas outlet 5 that is arranged in offset relationship with the hole 6 in the bottom of said chamber through which the gases enter from the flame arrester D. Said gas outlet 5 is controlled by a vent valve 7 herein illustrated as consisting of a horizontally disposed palate arranged inside of the gas chamber X and adapted to cooperate with a valve seat 8. Air is admitted to the gas chamber X by one or more automatic vacuum vent valves of any preferred construction, designated as an entirety by the reference character E, said vacuum vent valve E being equipped with an air inlet valve (not shown) that opens automatically and permits air to flow into the gas chamber X and thence through the flame arrester D into the tank A when the internal pressure of said tank drops to a certain approximate degree.

The volume control valve 7 of the valve C is normally held against its seat 8 by a spring 9 and a valve operating rod 10 is provided for moving the valve 7 in opposition to the spring 9. As shown in Figure 2, the valve operating rod 10 is arranged in a vertically disposed tubular member 11 whose upper end is attached to the bottom portion of the gas chamber X and whose lower end portion is attached to the plate 3 on which the flame arrester is mounted, the passageway 11 for the valve operating rod 10 being provided at its upper end with a flame

sealing device 12 of any preferred kind that will prevent a flame from passing downwardly through the valve rod passageway 11 into the tank A. The rod 10 is attached at its upper end to the volume control valve or vent valve 7 and at the lower end of said rod is a depending link 13 which carries a tripping block 14 (see Figure 1) which is so constructed and arranged that at a certain point in the upward movement of the roof B said tripping block will come in contact with one of the roof supporting beams 1, with the result that if the roof continues to move upwardly, the rod 10 will remain at rest and thus cause the control valve 7 to open or be unseated. In order to protect the gas outlet passageway 5 from the elements, a weather hood or shield 16 is mounted on the top side of the valve C, said hood being constructed so that it also serves as a housing for the spring 9 which normally holds the valve 7 seated.

In a control device of the construction above described, there is one passageway for the incoming air and outgoing gases, and there is a separate passageway for the pull rod 10 that actuates the volume control valve 7. Consequently, it is possible to provide the device with a single flame arrester that coacts with the vacuum vent valve and the volume control valve associated with the gas chamber. Another advantage of such a control device is that a flame arrester can be easily combined with the same without the necessity of making any changes in the flame arrester, due, of course, to the fact that the operating device which effects the unseating of the valve 7 is arranged in a passageway entirely separate and distinct, and at one side of the flame arrester through which the gases escape from the tank. In addition to the desirable features above mentioned, my improved valve C is inexpensive to construct, it is easy to install and it is of sufficiently rugged design to insure its functioning properly when the roof B of the tank moves upwardly and downwardly in the normal operation of the tank.

Having thus described my invention, what I claim as new and desire to secure by Letters Patent is:

1. A control device for storage tanks used to hold gases and volatile liquids, comprising a valve body having a gas chamber provided with an inlet through which gases enter said chamber from the tank, a vent valve for said chamber, and an operating device for said vent valve arranged out of the direct path of travel of the gases that enter said gas chamber from the tank.

2. The combination of a storage tank provided with a vertically movable roof, a valve body on said roof having a gas chamber equipped with an inlet for gases which escape from the tank, a vent valve for said gas chamber, and an actuating device for said valve adapted to be operated by the movement of said roof and arranged out of the direct path of travel of the gases that escape from the tank into said gas chamber.

3. A control device for storage tanks which are used to hold gases or volatile liquids, comprising a vent valve, a flame arrester arranged between

the tank and the body of said vent valve so as to form a passageway for gases that escape from the tank or for air that is admitted to the tank, and an operating device for said vent valve arranged entirely on the exterior of the flame arrester. 5

4. A control device for storage tanks, consisting of a valve body on the roof of the tank provided with a gas inlet and a gas outlet, said gas inlet communicating with the interior of the tank, a vent valve that normally closes said gas outlet, and an operating device for said vent valve arranged at one side of said gas inlet and provided with a portion that projects outwardly through a flame sealed opening in the casing of said valve. 10

5. A control device for storage tanks, comprising a flame arrester mounted on the roof of the tank so as to form a passageway for gases that escape from the tank, a valve body on said flame arrester having a gas chamber provided with a gas outlet, a vent valve for said outlet that is normally seated, and an operating device for said vent valve projecting outwardly through a flame sealed opening in said valve body and arranged outside of said flame arrester. 15

6. The combination of a storage tank provided with a breather type roof, a flame arrester mounted on the roof of said tank in alignment with a hole in said roof through which gases escape from the tank and through which air is admitted to the tank, a combined pressure relief and vacuum vent valve mounted on said flame arrester, and an operating device for a venting element of said valve arranged entirely on the exterior of said flame arrester and provided with a portion inside of the tank that causes said venting element to function when the roof of the tank reaches a certain approximate position during upward flexing of same. 20

7. The combination of a storage tank provided with a breather type roof, a flame arrester mounted on said roof in alignment with an opening in the roof so as to form a passageway through which gases can escape from the tank and through which air can be admitted to the tank, a valve body having a gas chamber that communicates with the main passageway of said flame arrester, an automatic vacuum vent valve for said gas chamber, a pressure relief valve for said gas chamber, an operating device for said pressure relief valve, and a passageway for said operating device arranged entirely on the exterior of said flame arrester. 25

8. A storage apparatus provided with a movable part whose position is adapted to change to vary the volume of the gas space of the apparatus, a control device carried by said movable part and provided with a chamber, a main passageway leading from said chamber to said gas space, a vent valve for said chamber, an actuating device for said vent valve adapted to be operated by the movement of the said movable part of the apparatus, and a passageway for said actuating device separate and distinct from said main passageway. 30
